ADJUSTABLE LABORATORY CLAMP

Leslie F. Vixler, Rocky River, Ohio, assignor to Labasco,
Inc., Durham, N.C., a corporation of North Carolina

Filed Mar. 6, 1959, Ser. No. 54,876

Term of patent 14 years

(Cl. D54—13)

Fig. 1 is a perspective view of an adjustable laboratory clamp, showing my new design;

Fig. 2 is a top plan view;

Fig. 3 is a side elevational view;

Fig. 4 is a right end elevational view;

Fig. 5 is a sectional view taken on the line 5—5 of Fig. 2, and

Fig. 6 is a sectional view taken on the line 6—6 of Fig. 2.

The essential features of my design reside in the portion shown in full lines.

I claim:

The ornamental design for an adjustable laboratory clamp, as shown and described.
